RAZOR BLADE HOLDER

William M. Sparr, Looneyville, W. Va.

Application November 27, 1945, Serial No. 631,107

3 Claims. (Cl. 30—330)

1

This invention relates to razor blade holders for use in stropping or sharpening the razor blade, and an object of the invention is to provide a blade holder with a stationary blade-engaging element or jaw and a movable coacting blade-engaging element or jaw, in which novel means are provided for opening and closing the movable jaw with respect to the stationary jaw and for clamping therebetween a razor blade to be stropped or honed.

A further object of the invention is to provide a bearing or tubular element having means to which the stationary jaw is attached and held, the said tubular element also acting as a bearing for an operating rod or shaft, having novel means of connection to the movable jaw.

It is furthermore an object to provide a tubular handle for the stropping device, in which means for operating the movable jaw is partially rotatable, and in which the operating means is accessible at the end of the handle, a condition which permits the free use of the handle during the sharpening operation without liability of the release of the blade by the jaws; it being furthermore the purpose of the inventor to have a threaded engagement between the inner wall of the handle and a member therein carrying the rod or shaft, so that by the frictional engagement of these threaded connections, release of the blade is prevented.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which:

Figure 1 illustrates a top plan view of a razor blade holder embodying the invention;

Figure 2 illustrates a side elevation thereof;

Figure 3 illustrates a longitudinal sectional view taken on the line 3—3 of Fig. 1;

Figure 4 illustrates a partial, sectional view on the line 4—4 of Figure 2, the handle being in elevation;

Figure 5 illustrates an end view showing in dotted lines the movable jaw in open position; and

Figure 6 illustrates a sectional view taken along the line 6—6 of Fig. 3.

Referring to the drawings, 5 and 6 denote a stationary and a movable jaw of any desired size and configuration. The jaw 6 is provided with

2

spaced tubular bearings 7, while the jaw 5 is provided with a single tubular bearing 8 adapted to be positioned intermediate the bearings 7. A handle 9 has a reduced tubular sleeve portion 10, which portion 10 extends between the bearings 7 and 8 when in assembled position, as shown in Figure 3. It will be noted that while the sleeve 10 engages both sets of bearings 7 and 8, it does not extend the full length of the outermost bearing 7.

In order to form the stationary jaw 5, the bearing 8 of this jaw is welded to the tubular extension 10, whereby jaw 5 becomes a part of the extension 10.

15 A rod 11, of a diameter to rotatably fit within the handle portion 9 and bearings 7, 8, is positioned within the handle portion 9 and bearings 7, 8 and projects slightly beyond the outermost bearing 7, as is clearly apparent in Figures 2 and 3. 20 An opening is provided in this end of the rod to receive a leverage pin 12 therethrough, which leverage pin is flush with the outermost bearing 7 of the jaw 6 and extends at right angles to the rod 11 substantially to the height of jaw 6, or it 25 may be midway of the jaw height. In this position the pin 12 is welded to the jaw 6 and to the rod 11 to become the movable jaw of the assembly.

The opposite end of the handle 9 has a reduced threaded portion 13 which is engaged with an interiorly threaded extension handle member 14. The rod 11 projects into the threaded extension 14 and is provided with a threaded end 15 which is anchored in a stem 16 that is externally threaded to engage the threads of the extension handle 14. A knurled knob 17 on the end of the stem 16 externally of the extension 14 is grasped by the operator for manipulating the rod 11 and rotating it, as will presently appear. 35 In order to secure the jaws in closed position, a threaded lock nut 18 is provided to engage the threaded portion 13 and bearing against extension handle 14.

As thus comprised, the nut 18 is rotated away 45 from handle 14, whereupon the operator manipulates the knob 17 which, through the rod 11 and the welded connections of the pin 12 thereto and to the jaw 6, rotates the jaw into the open position shown in Figure 5 in dotted lines. After 50 a blade has been inserted between the jaws, the reverse operation mentioned above takes place to close the jaws and the nut 18 is rotated into engagement with extension handle 14, the threaded connections serving to hold the parts ad- 55 justed.

I claim:

1. A razor blade holder comprising two cooperating jaws for holding a blade therebetween, one of said jaws having spaced tubular bearings and the other jaw having an intermediate tubular bearing fitting between the spaced bearings, a handle having a tubular sleeve within said bearings, means connecting the intermediate bearing to said sleeve, a rod rotatably extending through said sleeve and bearings, means connecting said rod to one of said spaced bearings, means on said handle to rotate said rod and open said jaw having spaced bearings, and means to secure said jaws in closed position.

2. A razor blade holder comprising two cooperating blades having tubular bearing portions, a handle having a reduced sleeve portion extending within the bearing portions, one of said bearings and its jaw being secured to said sleeve portion, a rod rotatably received within said handle portion, sleeve and bearings and extending beyond the outermost bearing, said rod having an opening in the projecting portion thereof, a pin positioned in said opening at right angles to said rod, means connecting said pin to said stem and to the other of said bearings and jaw, means carried by said handle to rotate said rod and its connected jaw to open position, and means to threadedly secure said jaws in closed position.

3. A razor blade holder comprising a stationary jaw and a movable jaw, a handle having a reduced end secured to the fixed jaw and a threaded end, a rod rotatable within the reduced handle end and connected to the movable jaw, said rod having a threaded end projecting beyond the handle threaded end, an extension handle having interior threads in its bore to engage the threads of the handle and threadedly secured thereto, a stem having exterior threads within the handle bore and threadedly secured to said handle, said stem also having threads receiving the threaded stem end and anchoring same thereto, a knob on said stem to actuate said rod, and a lock nut threadedly engaging said handle threaded end and bearing against said handle extension.
